(57) **CLAIM**

The ornamental design for a cane clip, as shown and described.

DESCRIPTION

FIG. 1 is a perspective view of a cane clip, showing my new design;

FIG. 2 is top plan view of FIG. 1;

FIG. 3 is a left side elevational view of FIG. 1; and,

FIG. 4 is a right side end view of FIG. 1.

The right side view of FIG. 1 is identical to FIG. 3, but rotated 180°. The left end view of FIG. 1 is identical to FIG. 4.
